J. G. SAUNDERS

WRENCH

Filed Oct. 17, 1923

UNITED STATES PATENT OFFICE.

JOHN G. SAUNDERS, OF CROSS PLAINS, TEXAS.

WRENCH.

Application filed October 17, 1923. Serial No. 669,167.

To all whom it may concern:

Be it known that I, JOHN G. SAUNDERS, a citizen of the United States, residing at Cross Plains, in the county of Callahan and 5 State of Texas, have invented certain new and useful Improvements in a Wrench, of which the following is a specification.

This invention appertains to novel improvements in pipe wrenches and the like 10 and the primary object of the invention is to provide an improved pipe wrench, which is particularly adapted for use on well casings and the like and which is so constructed as to preclude the crushing of the pipe or 15 casing, when the wrench is in use.

A further prime object of the invention is the provision of a novel pipe or casing wrench which will effectively grip the pipe or casing and prevent the slipping of the 20 said pipe or casing, the wrench being so arranged as to permit the easy and quick removal thereof from the pipe or casing irrespective of how the teeth of the wrench have 25 caught into the pipe or casing.

A still further object of the invention is to 30 provide an improved pair of back up tongs or wrench for well casings of the above character, which will be durable and efficient in use, one that will be simple and easy to manufacture, and one which can be placed upon the market at a small cost.

With these and other objects in view, the 35 invention consists in the novel construction, arrangement and formation of parts, as will be hereinafter more specifically described, claimed and illustrated in the accompanying drawings, in which drawings:

Figure 1 is a side elevation of the improved wrench.

Figure 2 is a detail perspective view of 40 the upper end of the master jaw and shank of the wrench, and

Figure 3 is a detail perspective view of the 45 companion jaw for the master jaw of the wrench, and

Figure 4 is a bottom plan view of the removable jaw of the wrench.

Referring to the drawings in detail, wherein 50 similar reference characters designate corresponding parts throughout the several views, the letter A generally indicates the improved wrench or back up tongs for well casings and as shown, the same includes the elongated shank 5, which gradually tapers

toward its rear end, as at 6. The shank 5 55 can terminate at its rear end in an eye 7 for facilitating the hanging up of the wrench or the like, if so desired, when the wrench is not in use.

The inner or forward end of the wrench 5 60 is provided with a master jaw 8 and a removable rigid companion jaw 9. The removable companion gripping jaw 9 is provided with a relatively short shank 10 for abutting engagement with the shank 5 and 65 the outer face of the shank 10 is provided with a pocket 11, the purpose of which, will be hereinafter more fully described. In order to facilitate the rigid connection of 70 the companion jaw 9 with the master jaw 8, the inner face of the jaw 9 is provided with a transverse rib 12, which is adapted to fit in a suitable groove 13 formed in the inner face of the jaw 8. The jaw 9 is formed 75 relatively longer than the jaw 8, and both of the jaws 8 and 9 are of an arcuate configuration so as to conform to the curvature of the pipe or casing, with which the wrench is 80 associated. The jaws 8 and 9 are each provided with active jaw faces 14 and 15 respectively, which are removably attached to the jaws 8 and 9 so that new jaw faces can 85 be used with the jaws 8 and 9, when the original jaw faces become worn or broken. As shown each of the jaw faces 14 and 15 are provided with transverse lugs 16, which 90 are adapted to fit in pockets 17 formed in the jaws 8 and 9 and these jaw faces can be retained in place by suitable machine screws 18 or the like. The active portions of the 95 jaw faces 14 and 15 have transverse biting teeth formed thereon, which gradually increase in height toward the outer edge of the master jaw 8, so that as the wrench is turned, a tighter grip will be had upon the pipe or casing. In order to prevent the 100 crushing of the pipe or casing, however, the outermost tooth formed on the jaw face 14 is decreased in height and rounded as clearly shown in Figure 1 of the drawing.

In order to detachably hold the companion jaw in position against slipping movement, when the wrench is in use, a locking cam 20 is pivotally connected as at 21 to a swinging yoke 22, which is in turn pivoted as at 23 to the shank 5 of the wrench A. This yoke 22 is arranged in relatively close 105 relation to the master jaw 8. The cam 20

is adapted to seat in the pocket 11 formed in the shank 10 of the jaw 9 and it is obvious that when this cam is operated so as to move the throw portion thereof in the pocket, the jaw 9 is held against movement.

The outer end of the jaw 9 is slotted as at 24 and a pin 25 extends across the slotted portion. A holding chain 26 of the sprocket type is provided for engaging about the pipe or casing and the inner end of the sprocket chain 26 is pivoted as at 27' to the shank 5 of the wrench. A adjacent to the jaw 8. The free end of the chain 26 is inserted through the slotted portion 24 of the jaw 9 and the extreme free end thereof can be provided with a transverse holding pin 27.

The shank 5 of the wrench adjacent to the outer end thereof can be provided with a pivoted shackle 28', to permit the same to be attached to the engine hitch.

In use of the improved wrench the companion jaw 9 is first placed in position as shown in Figure 1 of the drawing after which the wrench is placed in engagement with the pipe or casing. The chain 26 is now passed around the pipe and placed through the slot 24 and drawn into intimate engagement with the pipe as tight as is possible after which the wrench is turned. Prior to the turning of the wrench, one link of the chain is moved into engagement with the chain seat 28 formed in the inner surface of the jaw 9 on the inner walls of the slot 24, which prevents slipping of the chain.

Now it is obvious that during the rotation of the wrench that the teeth formed on the active jaw faces 14 and 15 will bite into the pipe and due to the increase in the length of the teeth, a tighter grip will be had on the pipe or casing as pressure is increased upon the wrench. However, crushing of the pipe or casing is prevented due to the shortening and the rounding of the last tooth formed on the jaw face 14.

When the wrench is to be removed from the pipe or casing, and it is found that the teeth have become deeply imbedded in the pipe, it is merely necessary to operate the cam 20 so as to release the shank 10 and remove the companion jaw 9 from out of engagement with the pipe or casing, after which the wrench can be quickly and easily removed from engagement with the pipe.

From the foregoing description, it can be seen that I have provided an exceptionally simple and durable wrench for well casings

and the like which will effectively accomplish the purpose intended.

Changes in details may be made without departing from the spirit or the scope of this invention.

What I claim as new is:

1. A wrench of the character described comprising a shank, a jaw rigidly carried by one end of the shank, a detachable companion jaw arranged to form a continuation of the first jaw for forming an arc of a circle therewith, means for clamping the detachable companion jaw rigidly in position, and a chain pivotally connected to the shank extending over the active faces of the jaws and arranged to detachably engage the companion jaw. 65

2. A wrench of the character described comprising an elongated shank, a master jaw rigidly carried by one end of the shank, a detachable companion jaw engaging the shank and forming a continuation of the master jaw, said jaws forming an arc of a circle, means detachably holding the companion jaw rigidly in position against movement, a pipe gripping chain pivotally connected at one end to the shank extending over the active faces of the jaws and adjustably connected at its opposite end to the companion jaw. 85

3. A wrench of the character described comprising an elongated shank, a jaw formed on the inner end of the shank, said jaw having a transverse groove formed in its inner edge, a companion jaw arranged to detachably engage the shank and form a continuation of the first mentioned jaw, a relatively short shank formed on the companion jaw for contact with the first mentioned shank having a cam seat formed therein, a pivoted yoke carried by the first mentioned shank, a pivoted cam carried by the yoke arranged to engage in the cam seat, the outer end of the companion jaw being provided with a slot, a chain seat formed in the inner walls of the slot, and a sprocket chain pivoted at one end to the first mentioned shank for engaging about a pipe and having its opposite end passed through the slot, any one of the links of the chain being adapted to fit in said chain seat. 100

In testimony whereof I affix my signature in presence of two witnesses:

JOHN G. SAUNDERS.

Witnesses:

TOM BRYANT,
SETH T. FIELDS.
